GABRIEL AUGUSTE MARIE VICTOR BIDOU, OF GRENOBLE, FRANCE, ASSIGNOR TO LA SOCIÉTÉ D'APPAREILLAGE MÉDICAL, OF GRENOBLE, FRANCE.

ARTIFICIAL LIMB.

1,316,347.

Specification of Letters Patent. Patented Sept. 16, 1919.

Application filed April 25, 1917. Serial No. 164,421.

To all whom it may concern:

Be it known that I, GABRIEL AUGUSTE MARIE VICTOR BIDOU, citizen of the Republic of France, and resident of Grenoble, France, post-office address Villa Le Gui, 27 Chemin Meney, have invented a new and useful Improvement in or Relating to Artificial Limbs, which improvements are fully set forth in the following specification.

- 10 The present invention relates to artificial limbs; and its essential object, briefly stated, is the provision of an improved device of the general class or character indicated, which shall correctly imitate both the bony 15 framework and the muscles of the natural limb, and shall possess the same joints, so as to enable the user to perform therewith nearly all of the movements possible with the natural limb.
- 20 The accompanying drawing illustrates, by way of example, one form of artificial leg constructed in accordance with the invention.

In said drawing:

- 25 Figures 1 and 2 are, respectively, a side elevation and a front elevation.

Figs. 3 and 4 are enlarged side and front elevations, respectively, of the knee joint.

- 30 Fig. 5 is an enlarged front elevation of the foot joint.

Figs. 6 and 7 are longitudinal and transverse vertical sections, respectively, of the said foot joint, on a still larger scale.

- Referring more particularly to said drawing, the improved structure shown comprises a metal framework, the various component members of which correspond in their relative position and arrangement to the parts or members of the bony framework of the human leg, and a system of connecting springs answering to the several main muscles thereof.

In Figs. 1 and 2, *a* indicates a metal tube, which answers, generally, to the femur or 45 thigh bone of the leg, and is connected at its upper end to a fork *b* provided with a plurality of arms or branches. This fork *b* acts as a holder or carrier for a stump support *c* provided at its bottom with a steel 50 cup *d*, to which the arms of the fork are riveted, the stump support being constructed of celluloid or other suitable material and being so shaped as to exactly fit the stump of the leg to which it is to be fastened.

- 55 The upper portions of the fork arms are

also riveted to the support, and the latter and the femur tube *a* are further secured together by means of metal braces *e*.

To the lower end of the tube *a*, there is attached, in the manner subsequently described, a longitudinally-adjustable metal rod or tube *f*, made in two parts which are arranged end to end and connected by a turn-buckle *g* to enable them to be moved toward or from each other to respectively decrease or increase the length of the tube and, hence, of the leg itself, as will be understood. The tube *f* answers to the tibia-fibula, or lower leg bones, of the human leg, and is connected to the tube *a* by a joint which corresponds to the knee-joint and is illustrated in Figs. 3 and 4. As therein shown, the confronting ends of the tubes *a* and *f* are fitted with co-operating knuckle-members *q'* and *r''*, the stems of which are inserted in the tube ends and rigidly secured therein. The part or member *q''* is formed with two spaced knuckles *q* and *q'*, which correspond to the condyles of the human leg and which receive between them the single knuckle of the part *r''*, the latter being provided at opposite sides of said knuckle with cupped seats or sockets *r* and *r'* for the reception of the condyle knuckles *q*, *q'*. The rounded edge faces of the knuckles *q*, *q'* are equipped with liners *s* of anti-friction metal, which play the part of cartilages in easing or cushioning the relative movements of the parts; and the pivot pin *s''*, which passes through the interfitting knuckles, is incased by a tube *s'* of anti-friction metal.

The foot portion of the leg is connected to the lower end of the tube *f* by means of a joint similar, in the main, to the knee-joint and described more in detail later. As shown in Figs. 1, 6 and 7, the foot consists of back and front parts *h* and *i*, which rest upon and are secured to the felt sole *k*, and are connected by a spring strip *j* (Fig. 1). The back part *h* is in the form of a stamped metal plate, and it is separated from the front part *i*, which is made of wood, by a space *h'*, this space enabling the necessary movement of the said parts *h* and *i* relatively to each other, the spring *j* returning said parts to normal horizontal position. The joint between the foot and lower leg preferably consists of an upper part or member *q''*, the stem of which is fixed in the lower end of tube *f*, and a lower part or member *r''*

100

105

110

which is fitted to a small tube t mounted in the back part or plate h of the foot. The upper part or member q'' of the joint is provided with two spaced knuckles q, q' , identical with those of the knee-joint, and the lower part or member r'' is provided with a pair of spaced, cupped seats or sockets r, r' , located at opposite sides of a central knuckle which fits between the first-named 5 knuckles, as shown in Figs. 5, 6 and 7. The tube t is arranged horizontally in plate h , and fits loosely within the part r'' on which the cupped sockets r, r' and the intermediate knuckle are formed, so that it serves as a 10 pivot about which the foot is enabled to turn 15 sidewise to a slight extent.

The system of connecting springs employed in conjunction with the parts above described, is preferably as follows:—At the 20 front of the tube a , there is arranged a set of vertical springs l , (four in the present instance), which are attached at opposite ends to upper and lower horizontal bars l', l'' , (Figs. 1 and 2); the upper bar being suitably connected by short links l^2 to the cup d 25 on the stump support c , and the lower bar being connected by relatively long links l^3 to a cross-pin m carried by the upper member of tube f , said cross-pin m having a stretching 30 mechanism m' associated with it to regulate the tension of the springs. These springs l correspond to the quadriceps muscles of the leg and serve to control the return of the parts to normal position, or 35 stated otherwise, to enable the leg to be extended and to make it execute the natural walking movements.

At the back of the leg, there is arranged 40 a spring n , corresponding to the biceps muscles and connected at opposite ends to two cross-pins n', n'' . The former of the two pins is carried by the tube a , and the latter by the upper member of the tube f , and one or the other of them may be ad- 45 justably mounted, or may have stretching means of some character associated with it to control the tension of the spring. The said spring serves to compensate the action of the springs l , and controls the bending of 50 the leg on, or with relation to, the thigh part.

The foot portion of the device has associated with it two springs o and o' , located, respectively, at the front and back thereof; the lower ends of said springs being suitably 55 attached to the metal plate h , and the upper ends thereof to the lower member of tube f adjacent its lower end, all as shown in detail in Fig. 6 and indicated diagrammatically in Fig. 1. In addition to the springs o and o' , two other springs p and p' (indicated in Figs. 2 and 7, but omitted 60 from Fig. 6) are utilized; these springs p, p' having their rear or upper ends attached to the part r'' embodied in the foot-joint in the 65 manner indicated in Fig. 7 and their lower

or front ends connected to plate h . As to the function of the several springs o, o', p and p' , it may be stated that the first spring o enables and controls the lifting movements of the foot, and, therefore, answers to the lateral and fibular-tibialis muscles of the foot; the second spring o' controls the bending movements of the foot and corresponds to the solear muscles; while the springs p and p' serve as the articular tendons, and act to restore the foot to normal position after having been turned in one direction or the other at the foot-joint.

The upper and lower parts of the device—that is to say, the support c and its carrier fork b and tube a , and the adjustable tube f , respectively,—are each provided with a set of what may be regarded as dressing or shaping springs, which are given the shape of the corresponding portions of the human leg. Thus, the upper springs v , which incase the parts c, b, a , conform to the shape of the thigh; while the lower springs v' conform to the shape of the calf of the leg and incase the part f . The said springs v 90 are connected to the support c and tube a in some suitable manner, and the springs v' are connected to the tube f .

The structure is completed by a curved plate or block u , which is attached to the lower end of a leaf spring u' , (Fig. 1), the latter having its upper end connected to tube a and acting to press the said plate outward. This plate or block plays the part of the knee, and preserves the appearance 100 thereof in the artificial leg, when the latter is dressed. To prevent displacement of the said knee plate, it may be connected by a link u'' to the upper member of the tube f .

While the structure above described is 105 adapted to take the place of the entire leg, it is to be understood that the lower portion thereof might be used alone in cases where only the lower part of the leg is lost.

I claim as my invention:—

1. An artificial leg, comprising an upper tube; a stump support carried thereby; a lower tube jointed at its upper end to the lower end of the upper tube; a foot jointed to the lower end of the lower tube; and a system of connecting springs between said lower tube and said upper tube and said foot.

2. An artificial leg, comprising an upper tube; a fork connected to the upper end thereof; a stump support fitted in and secured to said fork; a lower tube jointed at its upper end to the lower end of the upper tube; a foot jointed to the lower end of the lower tube; and a system of connecting springs between said lower tube and said upper tube and said foot.

3. In an artificial leg, the combination of upper and lower members jointed together at their confronting ends; a fork connected to the upper member; a stump support fitted 130

in and secured to said fork; a plurality of springs arranged at the front of the upper member; and connected at their upper ends with the stump support; a cross-pin carried by said upper member at the back thereof; a pair of cross-pins carried by the lower member, one at its front and the other at its back; link connections between said springs and the front cross-pin on the lower member; a compensating spring located at the back of said members and connected at opposite ends with the back cross-pins; and a foot connected to said lower member.

4. In an artificial leg, the combination of a member corresponding to the bone of the lower leg; a foot; a joint between said leg member and said foot comprising a pair of coöperating hinged parts, one formed with a pair of spaced knuckles and the other 20 formed with a single knuckle fitting between the first-named knuckles and having

a pair of cupped sockets at opposite sides thereof to receive said first-named knuckles.

5. An artificial limb, comprising, in combination, a pair of juxtaposed members jointed together at their confronting ends for relative movement; a fork provided on the free end of one of said juxtaposed members; a stump support fitted in and secured to said fork; and a multi-part member jointed to the free end of the other juxtaposed member, the component parts of said multi-part member being capable of movement relative to each other.

In testimony whereof I have signed this 35 specification in the presence of two subscribing witnesses.

GABRIEL AUGUSTE MARIE VICTOR BIDOU.
